APPLIQUÉ TYPE PANEL FOR CABINET DOORS OR THE LIKE

John R. Morgan, Wheeling, Ill., assignor to Amerock Corporation, Rockford, Ill., a corporation of Connecticut

Filed Dec. 19, 1966, Ser. No. 5,076

Term of patent 14 years

(Cl. D13—1)

FIG. 1 is a perspective view of an appliquéd type panel for cabinet doors or the like embodying my new design, the broken line illustration of several associated panels being shown for illustrative purposes only.

FIG. 2 is a front view of the medallion.

FIG. 3 is an enlarged side view of the medallion as seen from the left in FIG. 2.

FIG. 4 is an enlarged sectional view taken along the line 4—4 in FIG. 2.

FIG. 5 is an enlarged sectional view taken along the line 5—5 in FIG. 2.

I claim:

The ornamental design for an appliquéd type panel for cabinet doors or the like, as shown and described.
